UNITED STATES PATENT OFFICE.

ALFRED ANDERSON, OF CHICAGO, ILLINOIS.

DESIGN FOR A BRACKET FOR CURTAIN-POLES AND WINDOW-SHADES.

SPECIFICATION forming part of Design No. 33,588, dated November 20, 1900.

Application filed October 27, 1900. Serial No. 34,670. Term of patent 3½ years.

To all whom it may concern:

Be it known that I, ALFRED ANDERSON, a citizen of the United States, residing at Chicago, in the county of Cook and State of Illinois, have invented and produced a new and original Design for Brackets for Curtain-Poles and Window-Shades, of which the following is a specification, reference being had to the accompanying drawings, forming part thereof.

10 Figure 1 is a view in side elevation of a bracket, showing my new design. Fig. 2 is a perspective view thereof, and Fig. 3 is a rear end view in elevation.

As shown in the drawings, the leading or 15 material feature of my design consists of an upper horizontally-extending arm A, having near its outer end an upwardly-extending portion a, and at its outer end an upwardly-extending portion a', the said two portions 20 forming a U-shaped opening a², and at its other or inner end is provided with a transversely-extending part B, having an opening b on either side of the arm. Extending vertically from the inner end of the arm A is a

portion C, which has at its lower extremity a 25 short and horizontally-extending arm D, which is provided near its end with an upwardly and horizontally extending portion d and at its end with an upwardly-extending part d', which parts form a rectangular slot 30 or opening d², as is clearly shown in the drawings. The rear portion of the shorter arm D and of the portion C is provided with a circular part E, having an opening e in its lower portion.

Having described my invention, what I claim as new, and desire to secure by Letters Patent, is—

The design for a bracket for curtain-poles and window-shades, substantially as herein 40 shown and described.

In testimony whereof I have signed my name to this specification in the presence of two subscribing witnesses.

ALFRED ANDERSON.
